UNITED STATES PATENT OFFICE.

DAVID P. MANROSE, OF RIVERTON, IOWA.

PUMP.

SPECIFICATION forming part of Letters Patent No. 227,439, dated May 11, 1880.

Application filed March 8, 1880. (No model.)

To all whom it may concern:

Be it known that I, DAVID P. MANROSE, a citizen of the United States, residing at River-
ton, in the county of Fremont and State of
Iowa, have invented certain new and useful
Improvements in Pumps; and I do hereby de-
clare the following to be a full, clear, and ex-
act description of the invention, such as will
enable others skilled in the art to which it ap-
p pertains to make and use the same, reference
being had to the accompanying drawing, and
to letters or figures of reference marked thereon,
which forms a part of this specification.

My invention relates to lift-pumps; and it
consists in a submerged pump of peculiar con-
struction and arrangement of its operating
parts, whereby it is enabled to lift water from
deep wells with great facility and ease of op-
eration.

My invention is designed as an improvement
upon Letters Patent of the United States No.
211,414, granted to me January 14, 1879, for
improvement in pumps.

My present improvement consists more par-
ticularly in a submerged pump consisting of
two cylinders, one of which is stationary and
open at its lower end, and the other recipro-
cating, the latter or movable one, and which
is open at both ends, working within the sta-
tionary cylinder, and having a disk-valve at
one end and a screen at the opposite end, and
operated by suitable rod-and-lever connec-
tions.

It further consists in combining with the
pump-cylinders, as above described, ordinary
gas or steam pipe having communication with
the pump at its lower end, and its upper end,
or point where the water is discharged, sur-
mounted by an air-chamber, for the purpose of
rendering the delivery of the water from the
pump through the tubing uniform and con-
tinuous.

In the drawing, A represents an upright, of
wood or other material, to which the operat-
ing parts of the pump are attached; but they
may be secured in any other suitable way.

B represents a fixed or stationary cylinder,
entirely open at bottom, and surmounted by
a valve, b, and valve-box b'. Within cylinder
B is fitted another cylinder, C, so as to recip-
rocate therein by means of rod-and-lever con-

nctions. This cylinder C is open at both
ends, and is provided at top with a valve-
seat, c, and disk-valve D, secured at said top
in the following manner: A brace or rod, d, is 55
placed and secured diametrically across the
upper end of the cylinder C, and which car-
ries a short upright rod, e, having a cap or
nut, f. Upon this rod e is placed the disk-
valve D, it having a central opening for that 60
purpose, and a free but limited vertical move-
ment upon said rod between cap f and valve-
seat c.

A cross-bar, E, is secured to the lower end
of cylinder C, and projects outwardly suffi- 65
ciently far beyond cylinder B to receive the
lower ends of the double plunger-rods F F.

A screen, G, of any suitable or known con-
struction adapted for the purpose, is placed
across the lower end of cylinder C; but it may 70
be dispensed with if desired.

The upper end or head of stationary cylinder
B is provided with an ordinary weighted clack-
valve, b, opening outwardly from the cylinder
and inclosed by a valve-box, b', of any desired 75
construction. This valve-box b' receives the
lower end of the conduit-pipe H, constructed
of ordinary steam or gas pipe, surmounted by
an air-chamber, I, having a pump-spout, i, at
its lower end. This air-chamber serves the 80
purpose of rendering the supply of water
from the pump when in use continuous and
uniform.

The double plunger-rods F F work in guide-
ways secured to the side of cylinder B, and 85
are fastened at their lower ends to the pro-
jecting ends of cross-bar E, and at their upper
ends to the cross-bar K. To the cross-bar K
is secured the rod L, which in turn is fastened
to the lever O, to which the power is applied 90
to operate the pump.

The operation of the device is as follows:
Upon the lever being raised the cylinder will
move downwardly through its connection with
plunger-rods F F L and cross-bar K. This 95
downward movement of the cylinder raises
disk-valve D from its seat and allows the
water forced into the cylinder by said move-
ment to flow into cylinder B. Upon the lever
O being depressed it will raise the cylinder C, 100
the disk-valve seating itself by the pressure
of water above it, and the water will be forced

up through the pipe or tube H, the valve b opening and allowing it to pass, but immediately closing upon the cylinder again being depressed and retaining the water in the pipe H. Upon being again raised and depressed the operation will be repeated, and so on indefinitely, the supply of water from the tube being rendered continuous and uniform when in operation by means of the air-chamber I.

10 Having described my invention, what I claim as new, and desire to secure by Letters Patent of the United States, is—

1. In a force-pump, the stationary cylinder B, open at its lower end and provided at its upper end with the valve b, in combination with reciprocating cylinder C, open at both

ends and provided with disk-valve D and screen G, substantially as set forth.

2. In a force-pump, the stationary cylinder B, open at its lower end and provided at its upper end with the valve b, in combination with reciprocating cylinder C, open at both ends and provided with disk-valve D and screen G, and the conduit H, of ordinary gas or steam pipe, having the air-chamber I at its upper end, substantially as herein set forth.

In testimony whereof I affix my signature in presence of two witnesses.

DAVID P. MANROSE.
